UNITED STATES PATENT OFFICE.

FRANCIS H. RICHARDS, OF SPRINGFIELD, MASS., ASSIGNOR OF ONE-HALF
TO THE PRATT & WHITNEY COMPANY OF HARTFORD, CONN.

BLANK-PICKER FOR ENVELOPE-MACHINES.

SPECIFICATION forming part of Letters Patent No. 331,445, dated December 1, 1885.

Application filed October 16, 1884. Serial No. 145,065. (No model.)

To all whom it may concern:

Be it known that I, FRANCIS H. RICHARDS, a citizen of the United States, residing at Springfield, in the county of Hampden, State 5 of Massachusetts, have invented a new and Improved Blank-Picker for Envelope-Machines, of which the following is a specification, reference being had to the accompanying drawings, in which—

10 Fig. 1 is an elevation, partially in section, of such a picker embodying my improvements. Fig. 2 is a plan view of the under side of the same, also partially in section. Fig. 3 is a cross-sectional view in line *a a*, Fig. 2. 15 Fig. 4 is an elevation, similar to Fig. 1, of a modification in the construction of said improvements. Fig. 5 is a plan view of the under side of the same. Fig. 6 is a cross-sectional view in line *b b*, Fig. 5. Figs. 7 and 20 8 are similar cross-sectional views of other modifications.

Similar letters refer to similar parts throughout the several views.

This invention relates to certain improvements in the so-called "pickers" or "gummers," which are used in envelope-machines for taking up blanks by means of an adhesive substance previously applied to the under surface of said picker or gummer.

25 In the United States Patent No. 221,835, J represents a gummer and picker of an ordinary construction, arranged for gumming and picking up blanks, and in United States Patent No. 288,673, *e* represents the same arranged 30 to be used for gumming only. My improved picker or gummer is adapted to be used in either of those ways, as may be desired.

Heretofore in operating envelope-machines it has been found a difficult matter to 40 make a picker bear down upon the blanks with substantially a uniform pressure over the whole surface covered by said picker. Several expedients have been resorted to for overcoming the difficulty—such as an elastic or a tilting bed on which to place the pile of blanks—but thus far, in my opinion, without effecting a material improvement. Since the depth of 45 the pile of blanks is constantly varying, as well as the quality of the paper and of the

cutting out of it, it is obvious that the effect 50 of such expedients cannot be uniform.

The object of my invention is to secure the proper contact of the whole lower surface of the picker with the blank by means of an improved construction of the picker itself, whereby the lower surface thereof will not only conform in its general position to the blank, but it will also conform, owing to its flexibility, to all the undulations of said blank. This object I accomplish by means of the improvements in the construction of said picker, which are hereinafter described and claimed.

In the drawings, *S'* is the usual sliding shaft, to one end of which the picker is suitably fixed. *B* is the picker-frame, secured to 65 said shaft, and adapted to hold the other parts of the picker. *P* is a plate forming the face of the picker. This plate is flexible, and preferably covered with a layer of elastic material, as *L*—such as vulcanized rubber—for receiving 70 the gum. Said plate is secured to said frame *B* by means of a lateral-motion-resisting guide, *G*, and downward-motion stops *N*, the space between said plate and frame being occupied by a springy material, as *S* in Fig. 6, or a 75 series of springs, *S*. The aforesaid guides may be rods sliding through holes in frame *B*, and attached to plate *P* in any convenient manner, as in Figs. 5 and 6, or ears formed on or attached to said plate and inclosed by flanges on 80 said frame, as in Fig. 1, the function of both modes of construction being the same. The springs or springy material *S* should be such as will exert a sufficient downward force against plate *P* to bring stops *N*—which stops 85 may be nuts screwed onto the rods aforesaid—against frame *B*, thereby holding the gum-receiving surface in or nearly in a true plane, so that when the picker is brought down onto a pile of blanks it will transmit a sufficient 90 pressure from said frame through said plate to make the latter conform and adhere to the uppermost blank of the pile of blanks.

My improved envelope-blank pickers may be operated in connection with the usual gumming-roller and blank-carrying devices by means of the mechanism usually employed for so operating the old kinds of such pickers.

The operation of the picker itself is the same as the operation of the old kinds, except that, owing to its flexible and elastic construction, it conforms to the blank-pile more perfectly, and is therefore more effective.

Having thus described my invention, I claim—

1. An envelope-blank picker and gummer consisting of a suitable frame, a flexible plate or picker-face, lateral-motion-resisting guides, downward-motion stops, and springs acting

between said frame and plate, all combined and operating substantially as described.

2. In an envelope-blank picker, frame B, a flexible plate, P, rods G, springs s, and stops N, all combined, substantially as described, and shown in Figs. 4, 5, and 6, for the purpose set forth.

FRANCIS H. RICHARDS.
